UNITED STATES PATENT OFFICE.

CHARLES F. ROTHWEILER, OF SEATTLE, WASHINGTON.

PARTITION-SUPPORT.

1,184,263.

Specification of Letters Patent. Patented May 23, 1916.

Application filed May 24, 1915. Serial No. 30,040.

To all whom it may concern:

Be it known that I, CHARLES F. ROTHWEILER, a citizen of the United States, residing at Seattle, in the county of King and State of Washington, have invented certain new and useful Improvements in Partition-Supports, of which the following is a specification.

This invention relates to supports for partitions which are employed to divide bins, drawers, etc., into compartments; and its object is the provision of devices of this character which will be of simple and inexpensive construction and adapted to be conveniently applied with practically little loss of space.

The invention consists in the novel construction and adaptation of a metallic strip which is rolled or bent into channel shape and provided with a novel form of securing devices.

The invention is illustrated in the accompanying drawings, wherein—

Figure 1 is a plan view of a portion of a drawer divided by partitions which are secured by supports embodying my improvements. Fig. 2 is a transverse vertical section through 2—2 of Fig. 1. Fig. 3 is a detail vertical section through 3—3 of Fig. 1. Fig. 4 is a perspective view of a channel-bar which provides partition supports by cutting the same into suitable lengths.

In carrying out my invention, I form the partition supports from a strip of tin plate or other suitable material, which is rolled or bent into a channel shaped bar to provide a web member 5 with series of flange elements 6 extending rectangularly from its sides. As best shown in Fig. 4, these flanges are arranged in spaced pairs and affording portions of the web member therebetween which are unprovided with flange elements. The web is punched from the channel side and intermediate the adjacent pairs of flanges with a plurality of holes 7 and between the latter are desirably punched other holes 8. By punching said holes from within the channel sides of the bar, the material thus struck out furnishes bars or annular studs 7¹ and 8¹ for the purpose to be presently described.

I will explain the use of the supports with reference to a drawer having a front wall 9, side walls 10 and a bottom 11. To divide the drawer longitudinally, a transverse partition 12 is cut to a length equal to

the distance between the side walls 10 of the drawer less the thicknesses of the web members 5 of two supports. The stock (Fig. 4) is then cut off, as indicated in broken lines *x*—*x* of a length from the outermost ends, as 6¹ of the first pair of flange elements, to the ends, as 6², remote therefrom, of the pair of flange elements which will be within a length equal to or less than the inside depth of the drawer. The support thus cut from the channel bar will have its web member terminate at or near the ends of a pair of flange elements, while the other end of such member will 70 protrude as a lip 5¹. The lips of the cut-off pieces of the bar are then bent backwardly, as indicated by broken lines 5² in Fig. 4, and by full lines in the other views. The supports are then placed against the side 75 walls of the drawer and the extremities of partition 12 introduced and forced down between the flange elements of the respective supports, thereby causing the studs 7¹ and 8¹ of the upright portions of the supports 80 to be thrust into the side walls 10 of the drawer. Longitudinal partitions 13 and 14 may, in like manner, be engaged in supports secured to the drawer ends and transverse partitions. Ordinarily, the penetration of 85 the studs into the side walls will suffice to secure the supports and the associated partition against displacement. To render the supports, however, able to withstand any liability of working loose should the partitions shrink, as when green wood is used, I insert supplementary fastening devices such as brads 15 through the holes of the lips 5¹ into the subjacent drawer side or partition, as the case may be.

Among the advantages of the invention is the facility with which the supports may be cut to lengths and introduced and secured in predetermined positions, and when installed the partitions are prevented from 90 warping through the offices of the various flange elements.

What I claim, is—

The combination with a drawer or other receptacle and a partition, of supports for the partition, said supports each comprising a channel bar formed with a web member and flange elements extending rectangularly therefrom at each side of the web, said flange elements being arranged in spaced 105 pairs, said web protruding beyond said flange elements at one end to provide a 110

lip adapted to be turned down to engage over an edge of the receptacle wall and receive a fastening which engages in the receptacle wall, the other end of the web terminating substantially flush with the lower flange elements and positioned adjacent the bottom of the receptacle, circular struck-out portions formed in the web member and being rearwardly directed relative to the flange elements and located at points

between the pairs of flange elements to provide a clearance space for attaching the support.

Signed at Seattle, Washington, this 26th day of April, 1915.

CHARLES F. ROTHWEILER.
